Gudrik Amandus Johansson
per H. W. Pucker
Attorney.

UNITED STATES PATENT OFFICE.

FREDRIK AMANDUS JOHANSSON, OF HEDEMORA, SWEDEN.

TOOL-HOLDER.

1,280,750.

Specification of Letters Patent. Patented Oct. 8, 1918.

Application filed January 19, 1918. Serial No. 212,780.

To all whom it may concern:

Be it known that I, FREDRIK AMANDUS JOHANSSON, a subject of the King of Sweden, residing at Hedemora, Sweden, have 5 invented new and useful Improvements in Tool-Holders, of which the following is a specification.

This invention relates to elastic tool holders in which the tool holding portion or head 10 is yieldingly connected with the rigid body of the holder which otherwise is separated therefrom by a slit ending in a substantially cylindrical aperture.

In such tool holders the elasticity depends 15 in part upon the nature of the material of which they are made, in part, upon the size and position of the aperture and the slit. Heretofore it has not been possible to vary the elasticity of such holders without combining therewith a set of interchangeable 20 parts and the prevailing practice is to use a number of holders of different elasticity suitable for different tools and works. This, however, involves increased expenses while 25 the changes required result in a not inconsiderable loss of time. The present invention has for its object to remove this inconvenience by providing in a tool holder adjustable means whereby the elasticity of 30 the tool receiving head may be varied at will.

In the accompanying drawing a form of a holder according to the present invention is shown.

35 Figure 1 illustrates the holder in side-view, Fig. 2 from the upper side, while Figs. 3-5 show the pin in different positions in the aperture. Fig. 6 illustrates the pin in end-view and in side-view, partially in section, and Fig. 7 illustrates a holder for a lathe-steel while the holder in Figs. 1-6 is adapted for a thread-cutting tool.

In Figs. 1-2 and 7 1 is the handle of the holder, 2 the elastic fore part or tool receiving head, which is provided with a fixing member 3 (Fig. 2) or 4 (Fig. 7) for the tool 45 5 (Figs. 1 and 2) or 6 (Fig. 7). The elasticity of this part 2 is obtained by means of an aperture 7 and a slit 8 in the handle. According 50 to the present invention there is journalized in the aperture 7 a pin 9, which on a part of its circumference is cut off, thus making part of the pin eccentric to the aper-

ture. By turning the pin 9, for instance by means of a tool inserted in the holes 11, the 55 pin with its eccentric part 10 can be brought into different positions in relation to the slit 8. (See Figs. 3, 4 and 5.) It will be understood that by moving the pin 9 from the position shown in Fig. 5 to that shown in Fig. 60 3 or any other adjustable position a portion of the yielding neck 12 whereby the head 2 is connected with the body 1 will be rendered rigid and the elasticity of the holder will be varied accordingly.

65 This adjustment or turning of the pin can be effected after the fixing of the holder in its support and without necessitating the removal of the tool from the holder.

Having now particularly described the 70 nature of my invention and the manner of its operation, what I claim is:

1. In an elastic tool holder the combination with a rigid body and an elastic tool receiving head yieldingly connected with 75 said body and otherwise separated therefrom by a slit ending in a substantially cylindrical opening, of adjustable means in said opening for varying the elasticity of said tool receiving head.

80 2. In an elastic tool holder, the combination with a rigid body and an elastic tool receiving head connected therewith by a yielding neck but otherwise separated therefrom by a slit ending in a substantially cylindrical opening, of means engaging said opening for rendering rigid an adjustable portion of said neck.

85 3. In an elastic tool holder, the combination with a rigid body and an elastic tool receiving head connected therewith by a yielding neck but otherwise separated therefrom by a slit ending in a substantially cylindrical opening, of a pin rotatably mounted in said opening, said pin having a portion of its 90 periphery cut away and so arranged that the elasticity of the tool receiving head may be varied by rotating said pin in said opening.

95 In testimony whereof I have signed my name to this specification in the presence of 100 two subscribing witnesses.

FREDRIK AMANDUS JOHANSSON.

Witnesses:

AXEL WOLRATH,
CH. Z. JOHANSSON.
